UNITED STATES PATENT OFFICE.

THOMAS A. M. STEVENSON, OF WINSTON-SALEM, NORTH CAROLINA.

WATER HEATER.

Application filed February 12, 1926. Serial No. 87,890.

My invention relates to water heaters, and more especially to that type of water heater wherein the water is heated by a gas burner used in connection with a series of coils 5 against which the gas flame projects.

Another object of my invention is to provide in a water heater a series of coils for holding and conducting the water to be heated, and also to provide a compartment 10 rounding the coils and the flame, in which compartment water will be held for heating, the heat being thus consumed in heating the water rather than being allowed to heat the casing for the coils.

Another object of my invention is to provide a water heater in which the water will be passed through the flame several times before being allowed to leave the water heater.

Another object of my invention is to provide a water heater which can be easily drained in cold weather when there is danger of freezing.

Having thus stated some of the objects of my invention, a brief description of the different figures in the drawings will be given, in which—

Figure 1 is a vertical sectional view of my device;

Figure 2 is a cross-sectional view of the drain valve in open position;

Figure 3 is a cross-sectional view of the drain valve in closed position;

Figure 4 is a view taken along the line 35 4—4 in Figure 3;

Figure 5 is a plan view of my water heater;

Figure 6 is a cross-sectional view taken along the line 6—6 in Figure 1;

Figure 7 is a cross-sectional view taken 40 along the line 7—7 in Figure 1;

Figure 8 is a cross-sectional view taken along the line 8—8 in Figure 1;

Figure 9 is a cross-sectional view taken 45 along the line 9—9 in Figure 1.

A brief description of the different figures in the drawings having been given, a detailed description of the drawings will now be given, in which like reference characters 50 indicate corresponding parts throughout the drawings.

The numeral 10 indicates my water heater which has a base 11 which supports the whole heater. Secured to the upper portion 55 of the base 11 and to the inner surface thereof is the ring-shaped member 12 which has

on its upper surface an inner ring 13 and an outer ring 14 integral therewith. These rings are threaded on their inner faces.

Threadably engaging the inner surface of the outer ring 14 is the piece of tubing 15, which is preferably made of copper or brass, and threadably engaging the inner surface of the inner ring 13 is the piece of smaller tubing 16, made of the same material as the tubing 15.

The upper ends of the pieces of tubing 15 and 16 have a similar ring-shaped member 17 secured thereto by means of threads in the same manner as that just described for the lower ends of the pieces of tubing. This ring-shaped member 17 has a central disk portion 17^a having a cut-away portion 18 near the center thereof, the purpose of which will be set forth as the specification proceeds.

Located within the base portion 11 and secured to said base portion is the burner 20 which has a central hollow portion through which the pipe 21 passes. This gas burner 20 connects to an air intake portion 21' and to a gas pipe 22, which gas pipe has a valve 23 therein.

The source of water supply is indicated by the numeral 25. This pipe runs upward 85 over the top of the heater and through the hole 18 in the ring-shaped member 17 and forms itself into a coil 26, this being the outer coil in my water heater. The coil 26 extends downwardly until it reaches a point 90 just above the funnel-shaped member 27 where it curves inwardly and forms another coil 28 of smaller dimensions than the coil 26. This coil progresses upwardly to a point approximately on a level with the top 95 of the coil 26. The pipe forming both of these coils is led from the top of the coil 28 outwardly over both of the coils 26 and 28 and is joined to the inner tube 16 at the point 30, penetrating said tube 16 and communicates with the recess formed between the two pieces of tubing 15 and 16.

The connection of the inner coil 28 to the inner tube 16 is made either by soldering the pipe to the tube 16 or by a threaded connection if desired.

At the lower portion of the inner tube 16 a pipe 31 is joined thereto, the interior of the pipe 31 communicating with the space between the tubes 15 and 16. This connection may be made by soldering, brazing, welding, or by a threaded connection as de-

sired. This pipe 31 is connected to the T-shaped hollow member 32 located approximately midway between the inner walls of the inner tube 16, and also central over the burner 20. The upper portion of this T-shaped member 32 is connected to the lower portion of the funnel shaped member 27. This member 27 has an outer member 33 and an inner member 34. The member 34 fits 10 into the member 33, the walls of the members 33 and 34 being parallel to each other. The members 33 and 34 are fastened together at their topmost portions as at 35, and a pipe 36 leads from the inner surface 15 of the funnel-shaped member 34 up through the central portion of the inner coil 28, and out through the opening 18, and is there connected to the pipe 37 which is the hot water pipe of my device. This pipe 37 leads to the 20 storage tank for hot water, or to the different portions of the house in which my device is installed.

The lower end of the T-shaped member 32 has connected thereto the pipe 21 which extends 25 downwardly through the central portion of the burner 20 and connects with the cock 38. Also connected to this cock 38 is the pipe 39 which extends upwardly from the cock and is connected to the lower portion 30 of the outer coil 26 by means of a T-shaped member 40.

The cock 38 is placed in my device to enable 35 the water to be drained from all parts of the device when it is desired to drain the same. This cock is the conventional three-way cock having a Y-shaped passage 42 therethrough, and when in open position this Y-shaped passage connects with the openings 43, 44, and 46, as is evident in 40 Figure 2.

The water heater is put into operation in the following manner:

The base with the member 12 is made ready to receive the tube 16, which tube 16 45 is screwed into engagement with the ring 13, then the tube 15 is screwed into engagement with the ring 14, then the top member 17 is secured to the tops of the tubes 15 and 16. It will be noted that the tube 16 is slightly 50 higher than the tube 15, which allows the same to threadably engage the inner ring in the member 17 before the outer ring in this member engages the outer tube 15. When the operation is completed thus far the coils 55 are placed inside, the funnel shaped member secured into position, and the remaining parts connected together.

When fully assembled, the gas burner 20 is lighted, and the water feeds into the pipe 60 25, downwardly through the coil 26, up through the coil 28, then out into the space between the tubes 15 and 16, downwardly in this space, then through the pipe 31 into the T-shaped member 32, then upwardly through 65 the funnel-shaped member 27, and up

through the pipe 36 into the section 37 and into the hot water tank or to the different portions of the house.

Thus it is seen that I have devised a hot water heater which will be very efficient in 70 the heating of water, and one which will utilize the heat generated by the burner, allowing the minimum amount to escape.

Having thus fully described and explained my invention, what I desire to protect and 75 secure by Letters Patent is as follows.

I claim:

1. In a water heater, two cylindrical tubes of unequal diameters arranged concentrically to provide a space therebetween, means securing said tubes to each other at their ends and closing said space, a coiled pipe adapted to hold water secured inside of the smaller tube and extending downward in a spiral manner, a coil of piping mounted inside of the first mentioned coil, and joined to the outer coil at its lower portion, the last named coil winding spirally upward and being connected to the wall of the smaller tube and communicating with the space between the two tubes, a pipe communicating with the space between the two tubes near the lowermost portion of said space, said pipe being connected to a hollow funnel-shaped member located beneath the two coils, and a pipe leading from the upper portion of the funnel-shaped member up through the smaller coil and out of the top of the water heater, and heat producing means located beneath the funnel-shaped member. 95

2. In a water heater, two cylindrical tubes of unequal diameters arranged concentrically to provide a space therebetween, means securing said tubes to each other at their ends and closing said space, a coil of pipe curved spirally located within the second tube, a second coil of pipe located within the first coil of pipe, said coils of pipe being connected at their lower ends, the second coil communicating with the space between the two tubes, a hollow funnel-shaped member capable of holding water under pressure located beneath the coils and above said source of heat, a pipe leading through the lower portion of the smaller tube and being connected to the funnel-shaped member, a pipe connected to the upper portion of the funnel-shaped member, said pipe extending upwardly within the smaller coil of pipe and out through the cut-away portion in the member securing the tops of the two tubes together. 110

3. In a water heater, a coil of piping, a second coil of piping, the two coils being connected together at their lowermost points, a container adapted to hold and conduct water surrounding the said coils of pipe, the coils of pipe being in communication with said container, a funnel-shaped member capable of holding water located beneath the 120 125 130

coils of piping, a source of heat located below the funnel-shaped member, and means in communication with all of the above parts for draining the water therefrom.

- 5 4. In a water heater, two vertically disposed cylindrical members of different radial dimensions secured to each other at their ends so as to leave a space therebetween, a funnel-shaped member capable of holding 10 water under pressure located within the cylindrical members, a downwardly extending coil of piping located within the smaller cylinder and being connected to a source of water supply at its upper end, an upwardly 15 extending coil of piping connected to the lower portion of the first coil and having its upper end connected to and piercing the

inner cylinder, a pipe leading from the lower portion of the inner cylinder to the funnel-shaped member, a pipe leading from 20 the top of the funnel-shaped member upward inside of the smaller coil and out thru the top of the heater, whereby the water is directed downward thru one coil, upward thru the other coil, downward thru the space between the cylinders, up thru the funnel-shaped member and thru the vertically disposed pipe, and out thru the top of the heater.

In witness that I claim the foregoing as 30 my own I have signed my name to the specification, this the 6th day of Feb., 1926.

THOMAS A. M. STEVENSON.
